(57) **CLAIM**

The ornamental design for an antenna, as shown and described.

DESCRIPTION

FIG. 1 is a front elevational view of a first embodiment of an antenna showing my new design; FIG. 2 is a rear elevational view thereof; FIG. 3 is a top plan view thereof; FIG. 4 is a right side view thereof; FIG. 5 is a left side view thereof; FIG. 6 is a bottom perspective view thereof; and FIG. 7 is a front, left perspective view thereof; FIG. 8 is a front elevational view of a second embodiment of an antenna showing my new design; FIG. 9 is a rear elevational view thereof; FIG. 10 is a top plan view thereof; FIG. 11 is a right side view thereof; FIG. 12 is a left side view thereof; FIG. 13 is a bottom perspective view thereof; and FIG. 14 is a front, right perspective view thereof; FIG. 15 is a front elevational view of a third embodiment of an antenna showing my new design; FIG. 16 is a rear elevational view thereof; FIG. 17 is a top plan view thereof; FIG. 18 is a right side view thereof; FIG. 19 is a left side view thereof; FIG. 20 is a front, right perspective view thereof; and FIG. 21 is a bottom perspective view thereof; FIG. 22 is a front elevational view of a fourth embodiment of an antenna showing my new design; FIG. 23 is a rear elevational view thereof; FIG. 24 is a top plan view thereof; FIG. 25 is a right side view thereof; FIG. 26 is a left side view thereof; FIG. 27 is a bottom perspective view thereof; and FIG. 28 is a front, right perspective view thereof; FIG. 29 is a front elevational view of a fifth embodiment of an antenna showing my new design; FIG. 30 is a rear elevational view thereof; FIG. 31 is a top plan view thereof;

(Continued)

FIG. 32 is a right side view thereof;
 FIG. 33 is a left side view thereof;
 FIG. 34 is a bottom perspective view thereof; and,
 FIG. 35 is a front, right perspective view thereof.
